MACHINE FOR UNDERCUTTING.

1,408,662.

Specification of Letters Patent. Patented Mar. 7, 1922.

Application filed April 13, 1912, Serial No. 690,486. Renewed November 24, 1919. Serial No. 340,239.

To all whom it may concern:

Be it known that I, FRANK L. O. WADSWORTH, a resident of Sewickley, in the county of Allegheny and State of Pennsylvania, have invented a new and useful Improvement in Machines for Undercutting, of which the following is a specification.

This invention relates to improvements in mining machines and particularly machines of the sort used in making under-cuts below a mass of coal or similar material by moving a cutting apparatus laterally in a direction substantially parallel to the face or breast of the material.

One of the objects of the invention is to provide a mechanism by which the undercutting can be effected more rapidly than by the earlier means with which I am acquainted, this being accomplished by providing mechanical elements which give to the cutting devices two simultaneous movements, one a forward movement in the direction of the cut, and the other an angling movement in the plane of the cut, so that the cutter element, as a whole, is advanced, not in parallel with itself but with an oscillating or zigzag movement, by reason of which the cutting element is presented at each instant at a new angle to the surface or the line of the cut.

Another object of the invention is to provide simple and effective mechanism whereby such forward oscillating or "zig zag" movement of the cutter element may be automatically and continuously maintained without attention on the part of the operator or machine runner.

Other objects and advantages of the invention will appear in connection with the description of the operation indicated and in connection with the description of the particular mechanisms which are shown as adapted to carry out this operation.

In the accompanying drawings Figs. 1, 2 and 3 are diagrammatic views illustrating the positions which the cutter bar of the machine successively occupies in carrying out the method of "zig zag" cross-undercutting; Fig. 4 is a plan view of one form of machine adapted to the practice of the method; Fig. 5 is a front side elevation of said machine; Fig. 6 is a cross section on the line 6—6, Fig. 4; Fig. 6^a is a rear view of the machine in Fig. 4 with parts broken away; Fig. 7 is a perspective view of the

cam in said machine; Fig. 8 is a plan view of a portion of a second form of machine adapted to the practice of the method; Figs. 8^a, 8^b and 8^c are detailed views showing the sliding retarding rope wheel and its adjuncts, detached; Fig. 9 is a rear end elevation of the machine shown in Fig. 8; Fig. 10 is a partial diagrammatic side elevation showing a part of the train of driving gears employed in said machine; Fig. 10^a shows the swinging pinion-carrying frame detached; Fig. 11 is a plan view of a third form of machine by which the cross undercutting operations illustrated in Figs. 1 and 2 may be automatically carried out; Figs. 12 and 13 are respectively rear and front end elevations of the machine shown in Fig. 11, the rear elevation being partly in cross section on the line 12 of Fig. 11; and Fig. 14 is a rear side elevation of said machine. Fig. 15 shows one of the worms on the armature shaft and its worm wheel, detached. Figs. 16 and 17 are detailed views of the clutch lever shown in Fig. 14, detached.

I will first describe the general method of carrying out my "zig zag" operation of cross-undercutting and then describe more in detail the construction of the various mechanisms illustrated for the automatic performance of the method.

Referring to Fig. 1, 1 indicates the face or "breast" of the mineral in which it is desired to cut a slot or "kerf" either at the bottom of the vein, or at the top, or at some intermediate point between the top and bottom. This slot or kerf is comparatively narrow and machines of various types have been designed for cutting it by either a continuous or intermittent movement of the cutter bar or element. This invention relates particularly to the operation of continuous machines in which the cutting is performed by parts or elements which, while performing their cutting operation, are fed continuously forwardly in a direction substantially parallel to the face or breast, 1, of the mineral. The most usual type of cutter bar which is used in this class of machines is one in which the cutting elements or "bits" are secured to an endless chain, indicated in Figs. 1, 2, and 3 by the reference numeral 2; this chain being mounted on two sprocket wheels, the outer one 3 revolving freely in bearings at the end of the cutter bar 4, and the inner one 5 being mounted under the

frame 6 of the machine and positively driven by suitable mechanism carried by the said frame. In some types of these machines—such as diagrammatically shown, for example, in Figs. 1 and 2—the cutter bar 4 and frame 6 are rigidly secured together so that they move forward as a unit. In other types of machines—such as diagrammatically shown in Fig. 3—the cutter bar 4 is pivoted on the machine frame 6 so that it has an independent angling movement with respect to said frame.

In the previous use of both types of machine it has been the practice to advance the cutter bar 4 parallel to itself during the progress of the cross undercutting, said cutter bar being angled or inclined with respect to the mineral face 1 only occasionally, and in general only at certain times, as at the beginning and end of the cut (where the undercutting is being carried on in comparatively narrow rooms or stalls), or at times when the cutter bar encounters a hard spot or lump of foreign material in the vein and it becomes necessary to attack such spots at a new angle of cut.

According to the present method of operation there is imparted to the cutter bar 4 a continuously oscillatory or swinging movement first in one direction and then in the other while the machine as a whole is being fed forward in the direction of cut. Thus, starting with the position indicated at A, Fig. 1, the machine frame is first given an angular swinging movement in a contra-clockwise direction—as viewed from above—while it is advancing forward in the direction of the arrow, this simultaneous contra-clockwise and forward advancing movement being continued until the machine has reached the position indicated at B. The direction of the angling movement is then reversed so that the cutter bar element 4—and in this case the whole machine frame also—swings in a clockwise direction while it is advancing from the position B to the position C. The direction of angling movement of the cutter bar element 4 is then again reversed so that it swings once more in a contra-clockwise direction while advancing to the position D. These simultaneously angling and forward movements of the parts carrying the cutting mechanism are continued as the machine moves along the face or breast 1 of the mineral until the machine reaches the end of its cut. By thus combining the regular forward movement of the machine with the swinging or angling movement of the cutter bar element the line of engagement between the cutting bits and the kerf face of the cut is continually varied and the cutting proceeds more rapidly than is possible when this line of engagement is maintained parallel to itself. My improved method is

characterized by the fact that the angle of the cutter bar to the face of the cut is progressively varied while the cutter bar is moved forward, that is to say, the angling movement of the cutter bar does not take place suddenly, but gradually and over a considerable period of time.

In order to equalize the work and rate of cutting in equal intervals of time the rate at which the machine frame is fed forward along the mineral face 1 is further varied in such manner that the amount of mineral removed from the kerf while the machine is moving from the position A to the position B (or from the corresponding positions C to D or E to F) will be substantially equal to the amount of mineral removed from the kerf while the machine frame is moving from the position B to C (or from the corresponding position D to E). To do this it is necessary to make the rate of forward feed much less when the cutter bar is angling in a contra-clockwise direction than it is when the said bar is angling in a clockwise direction; and the change in the rate of forward feed will vary with and depend upon the extent of the angling movements of the cutter bar in the two directions. Thus, in Fig. 1, the rate of forward feed must be so varied as to cause a given point 7 on the machine frame to move from the position a to the position b (or from the corresponding positions c to d or e to f) while the machine frame is angling contra-clockwise, and in the same interval of time move from the position b to the position c (or from the corresponding position d to the position e) while the cutter bar is angling clockwise. The amount of material cut from the kerf while the machine is moving from the position A to the position B is indicated by the shaded area a b' of Fig. 1; while the amount of material cut out in the movement of the machine frame from the position B to the position C is indicated by the reversely shaded area b' c'. It is obvious that in order to equalize the work of cutting during the two successive cycles of machine movement these two areas must be substantially equal, and the rate of forward feed must be so varied in passing from one cycle to the next as to secure the desired equality in the amount of material cut during substantially equal time periods of operation. This determines the ratio of the distance a—b to the distance b—c.

The ratio between the distances a—b and b—c will depend upon the extent of the angular movement of the cutter bar while the machine is moving through the distance from a to c. This is clearly shown in Fig. 2 in which the angular swing of the cutter bar is very much greater than it is in the operation illustrated in Fig. 1. In this case

the rate of forward movement during the clockwise swing of the cutter bar—as for example the movement from the position B to the position C—must be very much greater than the rate of forward movement during the reverse swing of the cutter bar, which occurs while the machine is moving from the position C to the position D. As in the previous case the equalization of the work of cutting during successive cycles of operation requires that the amount of kerf material in the shaded area $b' c'$ of Fig. 2 shall be substantially equal to the amount in the adjacent shaded area $c' d'$; and in order to secure this equality the ratio between the forward movements $b—c$ and $c—d$ must be very considerably greater than the ratio between the corresponding distances required to secure said equality of cutting action under the conditions of machine movement illustrated in Fig. 1.

Fig. 3 shows diagrammatically a type of continuous side undercutting machine in which the cutter bar element 4' is pivotally mounted on the machine frame 6' so that the said cutter bar element can be angled without correspondingly moving the machine frame. In such types of machines the frame proper is usually mounted on tracks 8 laid parallel to the face or breast 1 of the mineral. In carrying out my method of zig zag cross-under cutting with this type of machine one proceeds exactly as with machines of the type conventionally shown in Figs. 1 and 2. That is to say the cutter bar 4' is given a uniform swinging or angling movement in a contra-clockwise direction while the machine with the attached cutter bar is being fed forward parallel to the face of the mineral from the position A to the position B; and then the angling movement of the cutter bar is reversed and given a uniform swinging movement in a clockwise direction while the machine is being advanced from the position B to the position C. Substantial equality of cutting duty during these two successive cycles of movement is secured by making the ratio between the distances $a—b$ and $b—c$ such that the amount of material removed from the kerf during the first cycle is substantially the same as the amount removed during the second cycle.

The process of zig zag cross-undercutting can be carried out with any suitable short-wall or long-wall machine having capacity for angular adjustment of its cutter bar, by providing such machine with a variable forward feed, and regulating the feed movements and the angling movements by hand in such manner as to slow down the forward movement of the machine while it is being angled contra-clockwise and accelerate the forward movement of the machine while it is being angled clockwise; these two movements being so controlled with respect to each other as to secure the desired equality in the amount of material removed in successive equal intervals of time. But it is preferred to avoid the necessity for such hand control and regulation by providing an automatically acting mechanism for properly timing and co-regulating the simultaneous angling and forward movements of the cutter bar and machine frame during the successive cycles of operation. Several forms of semi or partially automatic machines by means of which the zig zag method of cross undercutting can in part be carried on are shown in the companion application, Ser. No. 678,567 filed February 19, 1912. The present application shows three other forms of machine by which said method can be carried out in a completely automatic manner.

In the first construction shown in Figs. 4 and 5 the machine frame 6 is provided with a suitable base for its support directly on the floor of the mine. The cutter bar 4 may be of any suitable construction and is provided with the endless cutter chain 2 carrying cutter bits 9. The cutter chain is carried by the idle sprocket 3 at the outer end of the cutter bar 4 and by the driving sprocket 5 in the bottom hollow portion of the machine frame 6. The chain may be driven by any suitable motor, the drawings showing diagrammatically an electric motor 10 mounted on top of the frame 6, although a compressed air motor or other prime mover may be used. This motor is arranged with its driving shafts transverse to the main frame and cutter bar extension. Said driving shaft is provided at one end with a pinion 11 meshing with a spur gear 12 which rotates on a stud secured to the motor frame. Secured to the gear 12 is a pinion 13 which engages with the spur gear 14 secured to one end of a sleeve which rotates in a bearing 15 mounted on the machine frame. On the inner end of this sleeve is a mitre gear 16 which meshes with a corresponding gear 17 on the upper end of a vertical shaft 18 which passes down through the top plate of the machine frame 6 and carries at its lower end a spur pinion 19 engaging with the master gear 20 on the shaft of the chain driving sprocket 5. A suitable clutch 21, operated by handle 22, is arranged to connect and disconnect the pinion 19 to and from the vertical driving shaft 18 on which it is mounted. This is the main clutch for starting the cutter chain, or stopping it when it is desired to operate other parts of the mechanism without moving the cutting chain.

Also meshing with the mitre gear 17 is a corresponding gear 23 secured to the end of a sleeve which rotates in a bearing 24. Extending through the sleeves on which the gears 14, 16 and 23 are mounted is a shaft 25 on the end of which is secured the worm

- 26 engaging with the worm wheel 27. The shaft 25 has splined thereto and movable longitudinally thereon a clutch member 28 located between the two mitre gears 16 and 23 and arranged to be moved on said shaft 25 by the lever 29 so that it can be engaged at will with either of the gears 16 or 23, or placed, as shown, in an intermediate non-engaging position midway between them.
- 10 When the clutch is moved toward and engaged with the gear 16 the shaft 25 and worm 26 are driven directly from the gear 14 in the same direction as that gear revolves, and when said clutch is moved toward and engaged with the gear 23 the shaft 25 and worm 26 are driven in an opposite direction through the intervening gear 17.
- The worm wheel 27 is secured to a vertical shaft 30 which rotates in bearing 31 and 32, and carries the sprocket or chain wheel 33 which engages the feed chain 34 by means of which the machine is advanced along the face of the mineral. In the operation of the machine the front end of said feed chain 34 is secured to a jack or anchor 35 set close to the face of the mineral some distance in advance of the machine, while its rear end is secured to a jack 36 which will be set up near the face of the mineral when making the sumping-in cut, so that during the undercutting it is in the rear of the machine. The machine so far described is not in principle different from certain types of machine now in use for undercutting coal. It is only one type of machine which is adapted for carrying out the method of the present invention. Any type of machine which is used must provide means whereby it can be successively angled clockwise and contra-clockwise and whereby the rate of forward feed can be varied, so as to produce a substantially uniform cutting action at all times. In the machine of Figs. 4, 5, 6 and 7, these effects are produced by the following means:
- 45 Just in advance of the feeding wheel 33 and preferably substantially in line with the rear edge thereof, is a movable idler sheave 38 mounted on the outer end of the long arm of a lever 39 fulcrumed at 40 and carrying a nut 41 engaged by screw 42 for moving the sheave 38 toward and from the feeding wheel 33, to increase or decrease the rate of paying out of the rear or check portion of the feed chain 34, and thereby vary the angular position of the machine. The variation in the forward feed of the machine is secured by varying the rate of winding in the forward end of the feeding chain. This, in the form of machine shown in Fig. 4, is 60 accomplished by leading the forward end of said chain over an idler sheave 43 journalled to the machine frame, thence over an idler sheave 44 carried on the inner short arm of the lever 39, and thence over another 65 idler sheave 45 mounted on the machine

frame. When the lever 39 is swung in one direction it decreases the paying out movement of the rear or check end of the feeding chain, and simultaneously decreases the winding in movement of the forward end of said chain, and when said lever is swung in the opposite direction the opposite effect is produced. If the lever arm on which the sheave 38 is mounted was equal in length to the lever arm carrying the sheave 44 the movement of the lever 39 would result in an equal movement of both sheaves and the only result would be to equally decrease or equally increase the rate of paying out and winding in movements of the two ends of the cable. But by making the inner arm of lever 39 shorter than the outer arm a differential action is allowed whereby the change in the rate of the paying out movement is always greater than the change in the rate of the winding in movement, and a combined angling and accelerating (or retarding) movement is obtained. Thus, if the lever 39 is moved in a direction to carry the idle sheave 38 away from the feed wheel 33, that is, toward the right in Fig. 4, the machine is angled contra-clockwise and at the same time its forward feed is decreased; and if said lever is swung in the opposite direction, so as to cause the idle sheave 38 to approach the feed wheel 33, the machine is angled clockwise and the forward feed is accelerated.

As shown, the lever is oscillated from a cam 47 carried by the worm wheel 27, and engaging a roller 48 on one end of the spring controlled lever 49 fulcrumed at 50, and having its opposite end connected by link or other suitable means 51 with an oscillatory angle-shaped frame 52 mounted on the end of shaft 25 concentric with a pinion 53 secured to said shaft 25 and rotating therewith. Pinion 53 meshes directly with a relatively large gear 54 mounted in the oscillatory frame 52 and indirectly through an idler 55 with a smaller gear 56 also mounted in said oscillatory frame. The parts are so arranged that only one of the gears 54 or 56 can be simultaneously in engagement with gear 57 on the screw shaft 42. The cam 47 has a high portion 58 which holds the gear 54 in mesh with gear 57, and a low portion 59 which allows the spring on the lever 49 to bring the gear 56 in mesh with gear 57. In the operation of the machine 105 the frame 52 is rocked alternately in opposite directions, thereby driving the screw 42 alternately in opposite directions and oscillating lever 39 alternately in opposite directions to either simultaneously 110 but differentially increase or decrease the rate of movement of the feed and check portions of the chain to and from the machine thereby either accelerating the feeding speed while permitting the machine 115

to angle clockwise, or reversely retarding the forward feeding movement while angling the machine contra-clockwise. By this mechanism, therefore, the angular position of the cutter bar with reference to the line of cut is constantly changed, and the speed of moving the machine forwardly is so co-regulated that the cutting action is substantially uniform at all times. The amount of angling movement is determined by the pitch of the screw 42 and the ratio of the gears 53 and 57, and the proper relations between the angling movement and the forward feeding movement of the machine are effected by properly proportioning the length of the lever arms carrying the idle sheaves 38 and 44.

Figs. 8, 9 and 10 show a modified form of machine in which the oscillating lever 39 and idle sheaves 38 and 44 carried thereby are dispensed with. In this case the chain or rope 34 passes directly from stationary idler sheave 43 on the machine frame to a second idler sheave 60 on the machine frame, thence around chain wheel or rope drum 61 and over guide sheave 62 to the rear jack. The wheel 61 is driven in the same manner as in Fig. 4 from worm 26^a engaging worm wheel 27^a secured to the hub of the chain wheel or rope drum 61. The wheel 61, and worm wheel 27^a, rotate on a heavy stud, mounted on a carriage 63 slidable in ways 64 in the frame, said carriage having an internally threaded member 42^b engaged by the screw 42^a. When this screw is rotated so as to move the wheel 61 toward the right, viewing Fig. 8, a pull will be exerted on the rear or check end of the chain 34, thereby angling the machine contra-clockwise. This movement also causes the chain wheel 61 to rotate clockwise (or in the opposite direction to the rotation being imparted thereto by the worm 26^a) due to the fact that the worm wheel 27^a must roll along the surface of worm 26^a, which is made sufficiently long to permit the necessary movement. The forward rolling movement of the worm wheel 27^a on the worm 26^a while the latter is revolving thus results in a decrease in the angular velocity of the wheel 61 and since the wheel 61 is of materially greater diameter than the worm wheel 27^a this decreased angular movement results in a material peripheral retardation of the inner edge of the wheel with respect to the outer edge, thereby producing a differential effect on the ratio of paying out and winding in of the rear and front ends of the feeding chain 34, and thereby securing the necessary decrease in the forward feeding movement of the machine while the machine is angling contra-clockwise, which is required to secure uniform cutting action. When the chain wheel 61 is moved in the opposite direction exactly the opposite effect is secured, that is to say, the increase in the rate of paying out of the

rear or check end of the feed chain—which permits the machine to angle clockwise—is greater than the increase in the rate of taking up or winding in of the forward end of said chain which results in an accelerated forward movement of the machine.

In this case as before it will be noted that the simultaneous or co-operating angling and feed accelerating (or retarding) movements are effected by simultaneously but differentially accelerating or retarding the speed at which feed and check portions of the chain or cable 34 are respectively wound in and paid out; the variation in the rate of movement of the former being always less than that of the latter.

In this form of machine the screw 42^a is alternately rotated in opposite directions by the following mechanism:

Mounted on bearings 64 above worm 26^a so as to mesh therewith is a worm wheel 65 carrying a cam 66 having high and low portions engaging roller 67 on lever 68 fulcrumed at 69 and having its opposite end connected to oscillating frame 52^a mounted concentric with pinion 53, which engages directly with a gear 54^a and through an idler 55^a with a smaller gear 56^a, said frame and gears being so arranged that only one of gears 54^a or 56^a can be in engagement simultaneously with gear 57 on screw 42^a. These parts of the mechanism operate the same as the corresponding parts in Figs. 4, 5, 6 and 7.

Figs. 11, 12, 13 and 14 show another modified form of machine for carrying out the method. In this machine there are two winding drums, to wit, drum 75 for the front or feeding cable or rope 34^a and drum 76 for the check cable or rope 34^b. These two drums are mechanically independent of each other and are adapted to be simultaneously rotated but in opposite directions so that one of said cables or chains is wound up while the other is being paid out. The mechanisms for driving the two drums are at the opposite ends of the motor, and are the same with the exception that the mechanism at the rear or outer end of the machine has certain additions to that at the inner or forward end. A description of the mechanism at the outer end will suffice for both.

The motor 10^a is mounted on the frame 6 with its armature should lengthwise of said frame, and is provided at each end with a worm 77 meshing with a worm wheel 78 on a vertical shaft 79 mounted in suitable bearings in the frame. The vertical shaft 79 at the outer or rear end of the frame carries the pinion 19 which meshes with the master gear 20 of the cutter chain sprocket. This pinion is of course omitted on the corresponding shaft at the other end of the frame.

The shaft 79 also has loose thereon a spur gear 80 which meshes with a larger spur 1

6 gear 81 loose on a vertical shaft 82. The later at this lower end carries a worm 83 meshing with a worm wheel 84 secured to the winding drum. The gear 81 comprises the 5 lower member of a differential gear, the upper member being formed by a worm gear 85 also loose on shaft 82. The gears 81 and 85 are provided on their inner faces with beveled gear members 86, with which mesh 10 the interposed beveled gears 87 carried by the member 88 fixed to the shaft 82. This is an ordinary type of differential gear which will be understood without further description. The worm wheels 85 at the two ends of the 15 machine are engaged respectively by worms 90 and 91 carried by the longitudinal horizontal shaft 92. These worms have their threads of different pitches, so that rotation of the shaft 92 rotates the differential gear 20 elements 85 in such directions as to simultaneously but differentially accelerate or retard the rotary movement of the two winding drums 75 and 76 for a purpose herein-after described.

25 As far as described, the driving mechanism for the winding drums 75 and 76 at the two ends of the machine are identical except as noted, that is that the vertical shaft 79 at the rear end of the machine carries pinion 19 which meshes with the master gear of the cutter chain sprocket.

The feeding movement of the machine can be started or entirely stopped by means of clutch 93 operated by lever 94 and serving 30 to lock gear 80 to, or release said gear from the inner or front vertical shaft 79. Similarly, the movement of the check rope drum can be started or stopped by means of clutch 95 operated by lever 96 and serving to lock 35 gear 80 to, or release said gear from the outer or rear vertical shaft 79. In order that the movement of this check rope drum may be reversed at certain times,—as in sumping in operations, etc.—the clutch 95 is splined 40 to the rear shaft 79 between a pair of reversely arranged bevel pinions 97 and 98 loose on shaft 79 and in constant mesh with an intermediate idler pinion 99. The bevel 45 pinion 98 is integral with or secured to gear 80. The clutch member 95 is arranged to engage clutch faces on either of the gears 97 or 98 and lock either, but not both, to said shaft. When the clutch is engaged with the bevel pinion 98 the check rope drum is 50 revolved in such direction as to unwind or pay out the check rope at the same rate as the feed rope is wound up by the front drum; when the clutch 95 is engaged with the bevel pinion 97 the rear drum is revolved at the 55 same speed but in the opposite direction. The latter movement is not however utilized while the machine is cross undercutting. It is used only when the machine is being employed in sumping in, or is being drawn 60

around in the mine floor between cutting operations.

Secured to the upper end of the rear vertical shaft 79 is a sprocket wheel 100 which is connected by sprocket chain 101 with a sprocket wheel 102 integral with a bevel 70 pinion 103 which is in constant mesh with a pair of bevel gears 105 and 106, loosely mounted in reverse positions on shaft 92. Splined to said shaft 92, and longitudinally movable thereon intermediate gears 105 and 75 106, is a clutch member 107 having clutch faces arranged to engage clutch faces on either but not both of said gears 105 and 106. This clutch lever is adapted to be shifted back and forth to engage said gears 80 alternately by means of a lever comprising two members 108 and 109 both pivoted at 115 and adjustably connected by the slot and bolt connection 116, said lever at its lower end carrying roller 111 engaging a 85 cam 112 secured to the axis 130 of winding drum 76. This cam is of the same general character as that shown in Fig. 7 having a high part and a low part, the high part being adapted to hold the clutch 90 member 107 in engagement with the gear 105 and thereby drive the shaft 92 and differential gears 81, 85 in one direction, and the low part permitting the spring to throw the clutch member 107 into engagement with the gear 106 and thereby drive the shaft 92 and differential gears 81, 85 in the opposite direction.

With this form of machine the feeding cable 34^a is wound onto drum 75 while the 100 check cable 34^b is simultaneously unwound from drum 76. If it were not for the special mechanism described in the preceding paragraph which is provided for the purpose of angling and varying the feed, the 105 one cable would be wound up as rapidly as the other is unwound and a parallel feeding movement obtained thereby. The action of the cam 112 with the connections above described produces the necessary angling 100 movement alternately clock-wise and counter-clockwise and also provides for the necessary corresponding acceleration and retardation of the feeding movement so as to secure a substantially uniform cutting action 115 at all times. The gears 80 being constantly in mesh with the lower members 81 of the differentials would, in the event of the upper members 85 of said differentials remaining stationary, produce a uniform paying out 120 of the check cable and a uniform winding up of the feeding cable, and this effect is produced in case the clutch member 107 is held in intermediate position. But when the clutch 107 is in engagement with the pinion 105, the shaft 92 is rotated in one direction, and the upper members 85 of the two differentials are rotated in one (and the same) 125

direction, say, in a direction to accelerate the rotation of shafts 82 and, therefore, accelerate both the winding up of the feeding cable and the paying out of the check cable, but in varying degree, due to the difference in pitch of the worms 90 and 91; and when said clutch 107 is in engagement with the bevel pinion 106, the shaft 92 and the upper members 85 of the differentials are rotated in the opposite direction, say, in a direction to retard the rotation of the shafts 92, and again in varying degree, thereby producing a retardation of the winding up of the feeding cable and a greater retardation of the paying out of the check cable. For the production of these effects, it is of course immaterial in which direction pinion 103 is rotated, since the clutch is part of the time in engagement with the pinion 105 and for the other part in engagement with the pinion 106, and the necessary retardation and acceleration will be secured irrespective of the direction of the rotation of pinion 103. In this case, as in preceding cases it is only necessary that the design of the cam 112, i. e. the relative lengths of the high and low portions of said cam—shall be such as to equalize the angular swinging movements of the machine in the two directions, clockwise and contra-clockwise, while the drum 76 to which the cam 112 is secured is being alternately accelerated and retarded. Any desired ratio between the feeding and the angling movements may be allowed by varying the pitches of the worms 90 and 91.

In order that this effect may be produced by hand, the clutch 107 is also arranged for hand shifting. To this end, the arm 109 is formed in two parts, 40 pivotally connected at 115 and having a releasable connection at 116, such as a bolt on one member extending through an arch shaped slot on the other member. When this bolt is tightened up, the two members become a rigid arm and the clutch is shifted from cam 112. But when the bolt 116 is released, the cam no longer effects the clutch. The clutch can then be shifted by hand by the following means: Pivot rod 115 is 45 extended and on its end is provided with a crank or handle 118 by means of which rod 115 can be oscillated and the clutch shifted as stated (see Figs. 14 and 11).

All of the automatic machines above described operate on the same general principles and they are all obviously adapted to secure the necessary relation between the angling movements and the variation in the feeding movements that are diagrammatically illustrated in Fig. 1; in which, it will be observed, when the machine is angling contra-clockwise, there is a retardation not only of the feeding movement but also of the paying out of the check cable; while 60 when said machine is angling clockwise,

both the feeding movement and the paying out of the check cable are accelerated. By properly proportioning the differential rates of variation of these two movements any desired ratio between feeding and angling movements can be secured.

By constantly changing the angle of the machine, or the angle of the cutter relative to the face on which the cutter is acting, the speed of cutting is very greatly increased 75 and the same amount of mineral can be cut with a less expenditure of power than where the cutter moves continually parallel with itself, as is the usual practice. This "zig zag" method of undercutting has the further 80 advantage of enabling the machine to cut under or cut out hard nodules more readily and easily than when the line of the cut is kept unaltered. To attain the advantages 85 of this method it is not necessary to oscillate the cutter bar equally on both sides of a normal to the line of advance. In some cases it may be advantageous to swing the machine back and forth unsymmetrically with respect to that line; i. e. to swing it 90 in such a way that in one extreme angular position it is more inclined to the face of the mineral—or the line of advance—than it is in its other extreme angle position. This can be readily accomplished with any of 95 the automatic machines above described—as well as by hand—at any time during the cut by stopping the machine, disengaging the automatic shift mechanism and moving the angling mechanism, independently of the 100 feed mechanism. Then on reengaging the automatic shift mechanism and restarting the machine the operation will go on as before save that the machine frame in its oscillating angling movements will now swing 105 around a new mean angular position to the face of the mineral or the line of the cut.

As will now be readily appreciated by those skilled in the art the method can be carried out by various other forms of machines than those herein described and illustrated, either of the cutter chain type, or the rotary cutter bar type. By the term "cutter bar" in the claims it is intended to cover either a cutter bar with a chain cutter, such as illustrated, or a rotary bar provided with cutters arranged along its length. In either form the axis of the cutter bar extends parallel to the face of the cut.

By the term "cable" in the claims hereinafter made, it is intended to include any form of cable, either a Manila rope, a wire rope or cable, or a chain cable.

What I claim is:

1. In a cutter bar mining machine, the combination of a mechanism for continuously feeding and guiding the machine bodily along a coal face, and means acting automatically on the feeding and guiding mechanism while the machine is continu-

ously advancing for varying the rate of the feed and simultaneously varying the angular position of the cutter bar.

2. In a cutter bar mining machine, the combination of a mechanism for guiding and continuously feeding the machine along a coal face, and means acting automatically on said feeding and guiding mechanism for oscillating the axis of the cutter bar alternately in opposite directions clockwise and contra-clockwise while the machine as an entirety is bodily advancing to vary the angular relation of the said bar to the coal face and simultaneously retarding the feed of said bar when the machine is swinging contra-clockwise, and accelerating said feed when it is swinging clockwise.
3. A feeding and guiding mechanism for a mining machine comprising in combination, two cable elements adapted to be attached to fixed points of support, driving mechanism on the machine continuously engaging operatively with said cable elements, and means on the machine engaging with each element independently for automatically increasing or diminishing the rate at which the elements are respectively drawn in and paid out by said driving mechanism whereby the angular position of the machine frame is varied and simultaneously the rate of feed is also varied.

4. A feeding and guiding mechanism for a mining machine comprising in combination, two cable elements adapted to have their ends attached to fixed points of support, a driving mechanism on the machine adapted to have continuous operative engagement with said elements, and automatically operated means engaging the cable elements separately for simultaneously increasing or simultaneously diminishing the rate at which said elements are respectively drawn in and paid out by said driving mechanism, whereby the angular position of the machine is varied and simultaneously therewith the forward feed of the outer part of the machine is varied in a manner to accelerate the said feed when the machine is angled clockwise and to retard said feed when the machine is angled contra-clockwise.

5. A feeding and guiding mechanism for a mining machine having an outer frame

element and a forward projecting cutter element comprising in combination, two cable elements adapted to have their free ends attached to fixed points of support, driving mechanism on the machine adapted to continuously engage operatively with said elements, and an automatically operated differential mechanism engaging with both of said elements and arranged to simultaneously decrease or simultaneously increase the rates of effective movements of said elements respectively between said driving mechanism and both of said fixed points of support.

6. A feeding and guiding mechanism for a mining machine having an outer frame element and a forward projecting cutter bar, comprising in combination, two cable elements adapted to have their free ends attached to fixed points of support, driving mechanism on the machine adapted to continuously engage operatively with both of said elements, and an automatically operated differential mechanism engaging with both of said elements and arranged to swing the cutter bar contra-clockwise a predetermined distance with accelerated speed and then swing the frame with accelerated speed and move the bar relatively clockwise with retarded speed.

7. A feeding and guiding mechanism for a mining machine comprising in combination, two cable elements adapted to have their free ends attached to fixed ends of support, a driving mechanism on the machine adapted to continuously engage operatively with said elements, and an automatically operated differential mechanism engaging with both of said elements, said parts being arranged to have the bar swing contra-clockwise with accelerated speed while the frame is advancing with retarded speed, and then to advance the frame with accelerated speed while the bar is advancing with retarded speed and caused to swing relatively clockwise.

In testimony whereof, I have hereunto set my hand.

FRANK L. O. WADSWORTH.
